William J. Jackson
ATTORNEY.

UNITED STATES PATENT OFFICE

FREDERICK M. VENZIE, OF PHILADELPHIA, PENNSYLVANIA

CEILING AND WALL STRUCTURE

Application filed March 5, 1929. Serial No. 344,252.

The present invention, generally stated, relates to a wall or ceiling structure and has more especial relation to the provision of slabs for not only providing fire proofing 5 proclivities but also to provide acoustic properties so that unnecessary and vibratory noises or sounds are precluded.

The leading object of the present invention may be said to reside in the provision of a very 10 thin slab of cementitious material provided upon one face with a plurality of dished cavities and preferably upon its other face with a roughened surface for the application of plaster.

15 A further object of the present invention is to provide a slab of the character stated in which a series of the dished cavities are arranged to contain, wholly or in part, an asbestos filling tending to facilitate the acoustic 20 properties of the wall or ceiling as erected.

25 A further object of the present invention is to provide a slab of the character stated which may be erected by nailing the same to a partition, the structure of the slab being such that it is possible to nail the same to any existing structure.

30 A further object of the present invention is to provide a slab of the character stated in which the slab may be roughened upon its front surface to accept plaster, or may be finished so that plaster is not necessary.

35 With these and other objects in view, the invention consists of the novel construction hereinafter described and finally claimed.

35 The nature, characteristic features and scope of the invention will be more fully understood from the following description taken in connection with the accompanying drawings forming part hereof, and in which:

40 Fig. 1, is a fragmentary view in vertical section illustrating a manner of applying the slab of the invention to a partition, which may be a wall or a ceiling.

45 Fig. 2, is a fragmentary view in elevation illustrating the parts shown in Fig. 1.

Fig. 3 is a fragmentary view in perspective illustrating a portion of the slab of the invention.

50 Fig. 4, is a fragmentary view in vertical section illustrating details of construction

and particularly the roughened face of the slab as used for the application of plaster.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1 designates a wall, ceiling or other support to which is applied the slabs of the invention. Each slab comprises, as clearly shown in Fig. 3, a rectilinear member 2 of cementitious material and relatively thin in cross section, as clearly shown in Fig. 1. The slab 2 upon one face is provided with a plurality of dished cavities 3 arranged in pairs laterally considered and in alignment vertically considered. The slabs 2

are secured to a wall, ceiling, or other building structure by means of nails 4, as shown in Figs. 1 and 2, it being understood that the composition of the cementitious slabs is sufficiently tough to permit of the penetration of nails. These cavities or dished portions 3 are preferably rectilinear in contour and abut or are juxtaposed immediately against the building structure 1. When nailed to place the slabs thus provide an air space between the structure 1 and the slabs.

These air spaces serve to provide means to prevent the resounding of noises. In order further to deaden undesirable noises, some of the cavities 3 are completely filled with asbestos or similar material 5 and other of the cavities 3 are only partially filled with asbestos or similar material. Thus, some of the cavities 3 are completely filled with asbestos material, some partially filled with asbestos material, and others have no asbestos material therein at all.

In practice I prefer to roughen that face of the slab opposite the dished portions 3 as at 6. This roughened portion 6 in practice

has applied thereto a thin coating of plaster 7, see Fig. 1. In the connection, however, I wish it understood that instead of roughening the face of the slab 2 I may leave the face perfectly plane and finish in a manner to provide a wall or ceiling surface. In other words, the slabs may be finished with an exposed surface which is smooth and acceptable as a wall structure, or may be roughened as shown 10 in Fig. 4 to accept a coat of plaster.

What I claim is:

1. In a building construction, a slab of cementitious material which is relatively thin in cross section and is provided upon 15 one face with a plurality of dished cavities, arranged in pairs laterally considered and in alignment vertically considered, which dished face of the slab is arranged to be juxtaposed with respect to a flat partition or 20 ceiling to form an air space between the building structure and said slab.

2. In a building structure a slab of cementitious material which is relatively thin in cross section and is provided upon one face 25 with a plurality of unperforated dished cavities, and arranged in pairs laterally considered and in alignment vertically considered, which dished face of the slab is arranged to be juxtaposed with respect to a flat partition or 30 ceiling to form an air space between the building structure and said slab, and asbestos filling for a series of said dished cavities.

3. In a building construction a slab of 35 cementitious material which is relatively thin in cross section and is provided upon one face with a roughened surface and upon the opposed surface with a plurality of dished cavities, arranged in pairs laterally considered and in alignment vertically considered, which dished face of the slab is arranged to 40 be juxtaposed with respect to a flat partition or ceiling to form an air space between the building structure and said slab.
